E. G. GARTIN

DRILLING MECHANISM

Filed Dec. 21, 1922

UNITED STATES PATENT OFFICE.

ELMER G. GARTIN, OF CLAREMONT, NEW HAMPSHIRE, ASSIGNOR TO SULLIVAN MACHINERY COMPANY, A CORPORATION OF MASSACHUSETTS.

DRILLING MECHANISM.

Application filed December 21, 1922. Serial No. 608,807.

My invention relates to drilling mechanisms, and more particularly to rotation mechanism for use in connection with percussive drilling mechanisms.

An object of my invention is to provide an improved drilling mechanism. Another object of my invention is to provide an improved rotation mechanism for use with rock drilling mechanisms. A further object of my invention is to provide an improved drilling mechanism of very compact form in which a percussive motor actuates a drill steel and a second motor simultaneously causes rotation of the drill steel. Other objects and advantages of my invention will hereinafter more fully appear.

In the accompanying drawings I have shown for purposes of illustration one form which my invention may assume in practice.

In these drawings,—

Fig. 1 is a central longitudinal section through the illustrative embodiment of my invention.

Fig. 2 is a transverse sectional view taken on line 2—2 of Fig. 1.

My invention has been shown for purposes of illustration embodied in a percussive drilling apparatus which is generally designated 1 and which includes a cylinder member 2 in whose bore 3 a piston 4 is reciprocable, this piston being adapted to be reciprocated by fluid pressure admitted thereto through inlet ports 5 and 6 and distributed by a groove 7 formed in the piston to passages 8 and 9 opening into the bore of the cylinder at appropriate places. It will be noted that the passage 9 opens into the bore of the cylinder at the extreme end of the latter as well as at other suitable and usual points, the rear-most point of communication being designated 10. The piston 4 is herein also provided with a nose or striking member 12 which passes through an opening 13 in the front head 14 of the cylinder and percussively engages the rear end of a rock drill steel 15 which is engaged in a chuck member 16 and is provided with lugs 17 which cooperate with a portion 16' of the chuck mechanism so that rotation of the steel is impossible except as the chuck is rotated.

In my improved construction, the cylinder member 2 is provided with a rear head 18 through which a passage 19 opens, this passage communicating with a cylinder bore or

chamber 20 formed in a member 21 arranged at the rear end of the cylinder member 2. The opposite end of the chamber 20 is closed by a head 22 through which an opening 23 is formed and through this opening a short piston rod 24 formed on a piston 25 reciprocable in the chamber or cylinder 20 is movable. A spline and key connection, as indicated at 26, prevents rotation of the piston 25 as the latter is reciprocated. The piston rod 24 is likewise provided with one or more spiral grooves 27 with which spiral keys 27' formed on a pawl carrying member 28 are arranged to cooperate. The pawls on said pawl carrying member are adapted to engage, as in any usual and well known construction, internal teeth 29 on a gear 30 which is rotatable in a chamber 31 to the rear of the cylinder 20. The gear 30 meshes with a smaller gear 32 which is mounted upon a tubular shaft 32', which is engaged by a dental clutch 33 with a second tubular shaft 34. This last shaft carries at its front end a pinion 35 which meshes with a gear 36 formed on a chuck rotating sleeve 37. A rear head member 38 is arranged at the extreme rear end of the drilling mechanism and this member carries a cylindrical projection 39 surrounded by a groove 40, the projection 39 entering a bore 41 in the piston rod 24 and the recess 40 receiving the annular piston rod 24. A vent 42 permits the free movement of the piston rod in the recess 40. Air is adapted to be constantly supplied during drilling through the passage 45 and around the outside of the cleansing fluid supply tube 46, which last is supported in the end member 38. It will thus be evident that the pressure fluid supplied through the passage 45 and around the tube 46 exerts a constant pressure tending to force the piston 25 toward the right, or forwardly. It will, moreover, be evident that each time that admission occurs to the rear end of the cylinder 3 there will be admission through the port 19 to the cylinder 20 at the right hand side of the piston 25 in such manner that this piston will move toward the left due to the action of the air upon the greater area of the end of the piston 25. It will be noted that the vent 42 likewise vents the space to the left of the piston 25 in the chamber 20 by way of the straight and spiral grooves formed in the piston rod 24. It will be observed that suitable side rods 47 and 48, the latter of

which forms a bearing for the tubular shafts 32' and 34, maintain the parts of the drill in assembled relation.

From the foregoing description the mode of operation of this mechanism will be clearly apparent. Air having been admitted to the percussive motor, the piston 4 will be reciprocated and the drill steel will be hammered. As air is successively admitted to and exhausted from the rear end of the cylinder bore 3, pressure will be transmitted to and exhausted from the right hand end of the cylinder 20 and accordingly the piston 25 will be alternately moved in opposite directions by the air admitted through the port 19 and by the constant air pressure acting in the chamber 41. As the piston 25 reciprocates, the spiral grooves will also oscillate the pawl carrying member 28 and this, as it oscillates, will cause progressive rotation of the gear 30, which will in turn drive the pinion 31 and so, through the shafts 32' and 34, the pinion 35, and the pinion 36 will drive the chuck carrying member 37 and so cause rotation of the drill steel. It will thus be seen that I have provided coaxial percussive and drill rotating motors both of the reciprocatory type and that I have produced a very compact and efficient construction.

While I have in this application specifically described one form which my invention may assume in practice, it will be understood that this form of the same is shown for purposes of illustration and that the invention may be modified and embodied in other forms without departing from its spirit or the scope of the appended claims.

What I claim as new and desire to secure by Letters Patent is:

1. In a rock drilling mechanism, a percussive motor to actuate a drill steel, and drill steel rotation mechanism including a cylinder having a piston reciprocable therein and disposed at the rear end of said percussive motor, a common head for said cylinder and motor, a motive fluid conducting passage in said head allowing constant communication between the adjacent ends of said cylinder and motor, and means for controlling the reciprocation of said piston by said percussive motor.

2. In a rock drilling mechanism, a percussive motor, a steel chuck carried at the front end thereof and a steel rotation motor carried at the rear end thereof comprising a piston and cylinder, said piston having a tail rod, rotation mechanism associated with said tail rod for rotation thereby and including a rotatable side rod and a plurality of meshing gears one of which is attached to said side rod, and driving connections between said side rod and said chuck.

3. In a drilling mechanism, a percussive motor, a steel chuck, a rotation motor therefor comprising a cylinder, and piston therein, a tail rod carried by said piston, a rear head

carried by said cylinder through which said tail rod projects, and rotation mechanism between said piston and chuck actuated by said tail rod and including a pawl and ratchet mechanism disposed adjacent said head and a shaft disposed substantially parallel to said percussive motor.

4. In a rock drilling mechanism, a cylinder and piston, said piston having a reduced hollow extension, a member telescoping with the hollow portion thereof, means for subjecting said hollow portion to constant live pressure fluid during all movements of said piston and to vent constantly the end of the cylinder in which said extension is disposed, and means for intermittently subjecting the other end of the cylinder to live pressure fluid to cause reciprocation of said piston.

5. In a rock drilling mechanism, a drilling motor having a casing providing a cylinder bore, a piston therein, a drill steel actuated by said motor, a drill steel rotation motor having a separate cylinder with a reciprocable piston therein, means for subjecting a portion of one end of said latter piston to constant live pressure fluid during all movements thereof, and to simultaneously vent the adjacent end of the rotation motor cylinder, and means for intermittently subjecting the other end of said rotation motor piston to live pressure fluid to cause reciprocation thereof to effect rotation of the drill steel relative to said motor casing.

6. In a drilling mechanism, a drilling motor including a cylinder and front and rear heads therefor, a rotatable drill steel receiving chuck carried thereby, a drill steel rotation motor comprising a motor casing secured to said rear cylinder head, a rear head element therefor, an intermediate head member, a piston reciprocable in said motor casing and alined with the longitudinal center thereof, said piston having means cooperating with and extending through said intermediate head member, ratchet and pawl mechanism disposed in said rear head element and with which said piston cooperates, and operative connections between said ratchet and pawl mechanism and said chuck for rotating the latter.

7. In a drilling mechanism, a drilling motor including a cylinder and piston and a rotatable drill steel receiving chuck, rotation means for said chuck comprising a reciprocable piston arranged coaxially with said motor, a ratchet and pawl mechanism operated by said last-mentioned piston, a gear concentric with said ratchet and pawl mechanism and actuated thereby, a cooperating gear meshing therewith, and transmission means between said latter gear and said chuck including a transmission shaft disposed parallel with the longitudinal axis of said drilling motor.

8. In a rock drilling mechanism, a percus-

sive motor having a relatively stationary cylinder, a piston reciprocating in said cylinder in contact with the walls thereof and fluid distribution means for regulating the passage 5 of a working fluid through the motor to effect reciprocation of said piston, a drill steel percussively actuated by said motor, means for rotating said drill steel comprising a cylinder and piston motor having its axis aligned 10 with the axis of said percussive motor and arranged at the rear end thereof, and operative driving connections between said motor and the drill steel including a rotating element extending longitudinally of the machine, said fluid distribution means for said percussive motor also controlling said rotation motor.

9. In a rock drilling mechanism, a percussive motor having a relatively stationary cylinder and a reciprocable piston fitting in the bore thereof, a drill steel percussively actuated by said motor, a second motor arranged at the rear end of said percussive motor and having a cylinder coaxial with said first cylinder, a piston reciprocable therein having an area subjected to constant pressure and an opposed area in communication with one 20 end of the cylinder of said percussive motor, and operative driving connections between 25 said second piston and the drill steel for ro-

tating the latter including a rotating element extending longitudinally of the machine, and fluid distribution means for said percussive motor.

10. A rock drilling mechanism constructed in accordance with the terms of claim 9 wherein said driving connections comprise a ratchet and pawl mechanism actuated by said second motor, a gear intermittently rotated thereby, and means including a shaft parallel 35 with said motors for transmitting the rotation of said gear to said drill steel.

11. In a rock drilling mechanism, a percussive motor having a relatively stationary cylinder and a reciprocable piston fitting in the bore thereof, a drill steel percussively actuated by said motor, a second reciprocating motor having a cylinder coaxial with said percussive motor cylinder, a piston reciprocable therein, a common cylinder head between said cylinder and an aperture therethrough for establishing direct communication between the same, and mechanism for transforming reciprocating movement of said second piston to rotary movement and for 40 transmitting said rotary movement to the 45 drill steel.

In testimony whereof I affix my signature.

ELMER G. GARTIN.
